SELF LEVELING, STORING, AND DISPENSING APPARATUS

William J. Gibbs, East Rockaway, and Carl H. Larsen, Brooklyn, N. Y., assignors to American Machine & Foundry Company, a corporation of New Jersey

Application November 1, 1951, Serial No. 254,396

9 Claims. (Cl. 312—71)

This invention relates to self-leveling storing and dispensing apparatus, and more particularly, to units of this type which are especially well adapted for carrying very heavy weights.

Self-leveling storing and dispensing units heretofore designed have had the disadvantage that as the carrying capacity of the unit was increased, the large number of counterbalancing springs required resulted in the dispenser becoming bulky and cumbersome.

It is therefore an object of this invention to provide a self-leveling dispenser which will be capable of handling loads as heavy as two thousand pounds and above without materially increasing the dimensions of the self-leveling apparatus.

Another object of this invention is to provide a device for maintaining the carrier of the self-leveling dispenser free from tilting even when unevenly loaded with heavy material.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

Figure 1 is an isometric view, partly in section, of the self-leveling dispenser.

Figure 2 is a schematic side elevation of a modified form of the invention.

Fig. 1A is a sectional end elevation illustrating the apparatus from the end opposite to that disclosed in Fig. 1.

Figure 3 is also a schematic side elevation of another modified form of the invention.

Figure 4 is a plan view of Figure 3 taken on line 4—4.

Fig. 2A is a plan view, partly in section, taken on line 2A—2A of Fig. 2.

The apparatus used in Figure 1 to illustrate the invention consists of a base 10 and two vertical frames or uprights 12 and 14 extending upwardly from opposite sides of said base 10. Conventional sprockets 16 and 18 are mounted on opposite sides of the lower end of frame 12 and two similar sprockets 20, one of which is not visible, are mounted on opposite sides of the base of frame 14. The upper end of frame 12 supports a horizontal shaft 22 in a pair of suitable bearings 24 mounted on opposite ends of the frame 12. A similar shaft 26 is supported in similar bearings connected to opposite sides of the upper end of frame 14.

A carrier 28 is positioned to travel up and down between the vertical frames 12 and 14 and is supported in each of its four corners by sprocket chains. Shaft 22 supports a double set of sprockets 30 and 32 at one end and another set of double sprockets 34 and 36 at the opposite end of shaft 22. Shaft 26 has a similar set of double sprockets 38, 40 mounted at one end of the shaft 26 and another set of double sprockets (not shown) mounted on the other end of shaft 26.

The carrier 28 and the material M is counterbalanced

by calibrated tension springs S and S' mounted inside of the frames 12 and 14 so that regardless of whether material is added to or removed from the carrier, the top of the material is always maintained at a constant elevation.

5 The lower ends of springs S are anchored to suitable brackets 41 secured to the base of the frame 12 while the lower ends of springs S' are anchored to a similar bracket 42 fixedly secured to the lower end of frame 14. The upper ends of springs S are connected to a floating bar 44 while the upper ends of springs S' are connected to a floating bar 46. The bar 44 is secured at opposite ends to sprocket chains 48, 50 and 52. The travelling bar 46 is secured to one end of sprocket chains 54, 56, and 58.

10 The opposite ends of sprocket chains 50, 52, and 56 is secured to one side of the travelling carrier 28 while the opposite ends of sprocket chains 48, 54 and 58 are connected to the opposite side of the platform 28. The sprocket chain 48, as shown in Figure 1, travels over 20 the sprocket 30 downwardly and under the sprocket 18 and across the bottom of the carrier under sprocket 20 and then upwardly inside of the frame 14 and over sprocket 38 and downwardly again where it is connected at its end to the platform 28.

25 The sprocket chain 56 is mounted for travel in an opposite direction on the other side of the dispensing apparatus. The sprocket chain 56 is connected at one end to the travelling bar 46 and travels over a sprocket 47 (Figure 1A) mounted on the shaft 26 and downwardly 30 around a sprocket 49 at the base of frame 14 across the bottom of the base 10 and upwardly around a sprocket 16 where it again goes around a sprocket 36 and downwardly to the corner of carrier 28 to which it is secured.

The sprocket chains 50 and 52 are connected at one 35 end as previously mentioned, to the bar 44 and are connected at their opposite ends to the carrier 28 and pass around their respective sprockets 32 and 34. The sprocket chains 54 and 58 are connected at one end of the opposite sides of carrier 28 and are connected at their opposite ends to the floating bar 46. The sprocket chain 54 travels around sprocket 40 and chain 56 travels over a similar sprocket 55 (Figure 1A), both fixedly mounted on opposite ends of the shaft 26.

40 It will thus be evident from an inspection of Figure 1 and Figure 1A that all of the sprocket chains assist in interconnecting the counterbalancing springs S and S' with opposite sides of the carrier 28. The sprocket chains 48 and 56 also serve the additional purpose of tying in the shafts 22 and 26 for equal rotary movement in opposite directions. It will thus be apparent that if shaft 22 rotates in one direction, shaft 26 is compelled to rotate an equal amount in the opposite direction. In other words, positive rotary movement of equal amounts in opposite directions are imparted simultaneously to the shafts 22 and 26.

45 It will thus be apparent that if the carrier 28 is unevenly loaded, this might tend to force one side of the carrier 28 to descend at a greater distance than the other side of the carrier 28 except for the fact that the cross-over sprocket chains 48 and 56 positively rotate the opposite shaft mounted in the upper ends of frames 12 and 14. It will also be noted that by having the sprocket chains 48 and 56 travel in opposite directions, each chain prevents the other chain from accumulating any slack due to the 50 fact that shafts 22 and 26 are always compelled to move equal distances in opposite directions.

55 It will be appreciated that the shafts 22 and 26 can be interconnected in other suitable ways for equal movement in opposite directions and I have shown in Figure 2 and in Figures 3 and 4, a modified form of the invention which effects the same results as the apparatus shown in Figure 1.

60

In Figure 2, I have shown a base 60 having vertical frames 62 and 64 extending upwardly from opposite sides of said base 60. A shaft 66 is mounted for free rotary movement at the upper end of frame 62 and a shaft 68 is mounted for free rotary movement at the upper end of frame 64. The shafts 66 and 68 have a plurality of sprockets 70 and 72 fixedly mounted on each of these shafts. At the base of each frame 62 and 64 are mounted similar shafts 74 and 76 which are freely supported for rotary movement in suitable bearings mounted in opposite ends of the base 60. A carrier 78 is floatingly guided for movement up and down between the uprights 62 and 64.

A pair of sprockets 79 and 80 are fixedly mounted on opposite ends of shafts 74 and 76. A pair of endless sprocket chains 71 are trained around the sprockets 70 and 80. A similar pair of endless sprocket chains 73 is trained around sprockets 72 and 79. The shafts 74 and 76 are interconnected for equal movement in the same direction by an endless sprocket chain 82 which is trained around suitable sprockets 81 and 83 fixedly mounted on each of the shafts 74 and 76, respectively. A plurality of calibrated tension springs 84 and 86 are suitably attached at their upper ends to horizontal rods 85 and 87, respectively, the former being suitably secured to spaced chains 71, while the latter is attached to chains 73. Springs 84 and 86 are anchored at their lower ends to suitable brackets 89 and 91 fixed to the lower ends of the frames 62 and 64.

The carrier 78 is secured to the inside run of sprocket chains 71 while the opposite side of carrier 78 is secured to the outside run of sprocket chains 73. It will be evident from this construction that the shafts 66 and 68 are compelled to move equal distances in the same direction and thus prevent the carrier 78 from being tilted. As a consequence the carrier 78, even when unevenly loaded, is prevented from tilting.

Figures 3 and 4 illustrate a modified form of the invention incorporating compression spring in conjunction with counterbalance springs in addition to an anti-tilting device which is especially essential in units designed for heavy loads.

The apparatus shown in Figure 3 consists of a base 90 and a suitable vertical frame structure 92 projecting upwardly around the sides of said base. The carrier platform 94 at each of its four corners is secured to one end of a chain 96, each of which is supported by a sprocket 98, two of which are mounted on a horizontal shaft 100 while the other two are secured to a horizontal shaft 102. Shafts 100 and 102 are supported in suitable bearings provided in the upper portion of frame 92. The other end of each chain 96 is anchored to a suitable lug 104 also secured to the upper portion of frame 92. The downward projecting loop of each chain also engages with a floating sprocket 106, one pair of which is rotatably mounted on a floating shaft 108 while the other pair is rotatably mounted to a shaft 110. To shaft 108, as well as to shaft 110, are hooked a plurality of counterbalancing springs 112, each of which at its lower end is anchored to a suitable bracket 114 secured to the base 90.

To permit very heavy loads to be placed on the carrier platform 94, the latter may be furthermore supported by means of a plurality of calibrated compression springs 116 confined in vertical position between the base 90 and the bottom portion of the carrier platform 94. It will thus be apparent that the compression springs or tension springs can be used alone or in combination as desired. To eliminate any tilting action of the latter in case of an uneven distribution of the heavy load on the platform, an endless chain 118 engages a sprocket 120 on shaft 100 and a sprocket 122 on shaft 102. Both sprockets are rigidly mounted on their respective shafts 100 and 102 and the chain is led in criss-cross fashion over two other idler sprockets 124 and 126 which permits the proper synchro-

nized and opposite rotation of shafts 100 and 102 and prevents the platform 94 from tilting at any time. Sprocket 124 is pivotally mounted to a stud 128 and sprocket 126 is rotatably supported by a stud 130. Both studs are suitably held by the base 90.

To assure smooth sliding at the crossing point of chain 118, a suitably mounted separating and guide plate 132 is provided.

The invention above described may be varied in construction within the scope of the claims, for the particular device selected to illustrate the invention is but one of many possible embodiments of the same. The invention, therefore, is not to be restricted to the precise details of the structure shown and described.

What is claimed is:

1. In a self-leveling storing and dispensing apparatus, a base, uprights extending upwardly from said base, a material supporting carrier movable up and down between said uprights, shafts extending across the upper ends of each of said uprights, bearings mounting each of said shafts for free rotary movement, sprockets fixedly mounted on each of said shafts, sprocket chains trained over said sprockets and connected with one portion of said carrier, and calibrated tension springs connected at one end with another portion of said sprocket chains and at the other end to a stationary part of said apparatus and additional means interconnecting said shafts for equal positive movement in both directions of rotation to compel said shafts and sprockets to always move equal distances.

2. In a self-leveling storing and dispensing apparatus, a base, uprights extending upwardly from opposite sides of said base, a material supporting carrier movable up and down between said uprights, a shaft extending across the upper ends of each of said uprights, bearings mounted on each of said uprights for freely supporting each shaft for rotary movement, sprockets fixedly mounted on each of said shafts, calibrated counterbalancing springs having one end maintained free from movement, sprocket chains passing over said sprockets and interconnecting the other end of each of said calibrated counterbalancing springs with the carrier, and means interconnecting said shafts for positive movement in both directions of rotation to cause said shafts and sprockets to always rotate equal amounts.

3. A self-leveling storing and dispensing apparatus comprising, a base, a first and second upright extending upwardly from opposite sides of said base, a material supporting carrier, shafts extending across the upper ends of each of said uprights, sprockets fixedly mounted on each of said shafts, calibrated counterbalancing springs connected at one end to said base, a first traveling horizontal bar connected to the other end of a predetermined number of said calibrated counterbalancing springs, a second traveling horizontal bar connected to the other end of a predetermined number of said calibrated counterbalancing springs, a first sprocket chain trained over a sprocket on each of said shafts and connected at one end to one side of said material supporting carrier, a second sprocket chain trained over a sprocket on each of said shafts and connected at one end to the opposite side of said material supporting carrier, means connecting said first chain to said first bar, means connecting said second chain to said second bar, one set of sprocket chains trained over sprockets on the shaft at the top of said second upright and connected at one end to the second bar and at the other end to the side of said carrier adjacent the second bar, and a second set of sprocket chains trained over sprockets on said first shaft and connected at one end to said first bar and at the other end to the side of said carrier adjacent said first bar.

4. A self-leveling storing and dispensing apparatus comprising, a base, a first upright extending upwardly from one side of said base, a second upright extending upwardly from the opposite side of said base, a first

rotatable shaft mounted across the upper end of said first upright, sprockets mounted on said first shaft, sprockets mounted at the bottom of said first upright, a second shaft rotatably mounted at the upper end of the second upright, sprockets mounted on said second shaft, sprockets mounted at the base of the second upright, a first set of calibrated tension springs having one end connected to the base of said first upright, a second set of calibrated tension springs having one end connected to the base of said second upright, a material supporting carrier mounted for up and down movement between said first and second uprights, a first sprocket chain traveling over sprockets fixedly mounted on said shafts and under the sprockets mounted at the base of said first and second uprights to interconnect the other end of the first set of calibrated springs with the side of said carrier adjacent the second upright, a second sprocket chain traveling over sprockets mounted on said shafts and under sprockets mounted at the base of said first and second uprights to interconnect the other end of said second set of calibrated springs with the side of the carrier adjacent said first upright, one set of sprocket chains passing over sprockets fixedly mounted on said first shaft to interconnect the first set of calibrated countersprings with the side of the carrier adjacent the first set of calibrated counterbalancing springs, and a second set of sprocket chains traveling over sprockets mounted on said second shaft to interconnect the second set of calibrated counterbalancing springs with the side of the carrier adjacent the second set of calibrated counterbalancing springs.

5. A self-leveling storing and dispensing apparatus comprising, a base, a first upright extending upwardly from one side of said base, a second upright extending upwardly from the opposite side of said base, a first sprocket carrying shaft rotatably mounted across the upper end of said first upright, a second sprocket carrying shaft rotatably mounted across the upper end of said second upright, sprockets mounted at the lower end of said first and second uprights, a first endless sprocket chain traveling in a closed path around the sprockets at the upper and lower ends of said first upright, a second endless sprocket chain traveling around the sprockets mounted in the upper and lower ends of said second upright, a carrier platform connected at opposite sides to said first and second endless sprocket chains, calibrated tension springs connected to said first and second sprocket chains for counterbalancing material supported on said material carrying platform to maintain the upper layer of material thereon at a predetermined constant elevation, a third endless sprocket chain interconnecting the sprockets at the base of said uprights to prevent the carrier platform from being tilted to cause the first and second sprocket chains to be positively rotated together equal amounts in either direction.

6. A self-leveling storing and dispensing apparatus comprising, a base, uprights extending upwardly from opposite sides of said base, a carrier platform movable up and down between said uprights, calibrated compression springs positioned between said carrier platform and said base, pairs of spaced sprockets mounted at the upper and lower ends of each of said uprights, a shaft interconnecting at least one pair of spaced sprockets in each upright, a sprocket chain for compelling the sprockets in each of said uprights to be positively moved in either direction of rotation for like amounts of rotation, and means securing said carrier platform to sprocket chains moving around sprockets supported in the upper end of said uprights to maintain the carrier platform horizontal at all times.

7. A self-leveling storing and dispensing apparatus comprising, a base, uprights extending upwardly from opposite sides of said base, a material carrier platform traveling up and down between said uprights, a pair of spaced sprockets mounted at the upper and lower ends of each upright, an endless sprocket chain interconnecting the sprockets mounted at the base of each upright for positive and equal amounts of rotation in both directions of travel, a first set of endless sprocket chains interconnecting the sprockets at the top and bottom of said first uprights, a second set of endless sprocket chains interconnecting the sprockets at the top and bottom of said second upright, means for securing opposite sides of said carrier platform to the first and second set of endless sprocket chains, and calibrated tension springs connected to the first and second set of sprocket chains to exert a counterbalancing force through said sprocket chains on the material carrier platform to maintain the top of the material at a constant predetermined level.

8. A self-leveling storing and dispensing apparatus comprising, a base, uprights extending upwardly from opposite sides of said base, a carrier platform movable up and down between said uprights, calibrated compression springs positioned between said carrier platform and said base, a shaft carrying spaced sprockets fixedly mounted thereon at the upper end of each upright, spaced sprockets mounted at the base of each upright, calibrated tension springs positioned adjacent one upright, a set of sprocket chains passing over the sprockets mounted on the shaft at the upper end of said upright to interconnect one side of the material supporting platform with said calibrated tension springs, calibrated tension springs positioned adjacent the other upright, a set of sprocket chains passing over sprockets mounted on the shaft supported in the upper end of the said upright to interconnect the other side of said material supporting platform with said calibrated tension springs, and a cross-over endless sprocket chain interconnecting the sprockets mounted on the shafts carried at the upper end of said first and second uprights to cause said sprockets to always move equal amounts in both directions of rotation to maintain the material supporting carrier horizontal at all times.

9. In a self-leveling, storing and dispensing apparatus a base, uprights extending upwardly from said base, a material supporting carrier movable up and down between said uprights, sprockets mounted at the upper ends and lower ends of each of said uprights, sprocket chains trained over said sprockets, means connecting opposite sides of said carrier to said chains, means interconnecting said sprockets and chains to positively compel said sprockets and chains to all move equal distances in either direction to maintain said carrier free from tilting, and calibrated tension springs having one end maintained stationary and the other end connected with said chains for effecting a counterbalancing action on the carrier to maintain the upper layer of material supported thereon at a constant elevation.
